ADVERTISING NOVELTY

Leon H. Amdur, Brooklyn, N. Y.

Application January 18, 1939, Serial No. 251,559

10 Claims. (Cl. 283—6)

This invention relates to advertising novelties and the like. Broadly, the invention contemplates the more or less permanent closing of the free edges of two succeeding sheets of a magazine, booklet, folder and the like, so that the printed matter on the two inner pages of the closed sheets cannot be discerned, and the provision in at least one of the outer exposed pages of the pair of closed sheets, of a flap or flaps slit 5 on three sides; such flap or flaps, which may be the outline of an object or otherwise harmonized with the picturization appearing on that page, will normally conceal the message carried on the inner page and thus require manipulation 10 on the part of the reader in folding the flap or flaps back (on the unslit side) in order to bring to view the message on the inner page of the other one of the said pair of sheets, and also the message on the reverse side of the flap 15 itself.

The novelty of this invention may be incorporated as part of an otherwise regular magazine, book, booklet, folder, and the like, or it may be employed as a separate piece. Instead 20 of slitting the three sides of the flap or flaps, these sides may be perforated, scored or the like, which must be broken in order to enable the flap to be opened, so that the reader is given the privilege of opening the flap himself and being 25 the first to read (at least in that particular article) the message there appearing. The top and bottom edges of the pair of succeeding sheets 30 as well as the free edges, may be closed or sealed. In this case there may be deposited between the closed sheets (which thus form a pocket), a card, slip, coupon, premium or the like, which can only be abstracted through the flap, which must be first folded back and, where the three edges are perforated rather than slit, must first be 35 broken—in this manner positive assurance is had that the recipient of the article or the purchaser of the magazine or book will find the coupon or premium intact.

For the attainment of these and such other 40 objects as may appear or be pointed out, I have shown an embodiment of my invention in the accompanying drawing, wherein:

Fig. 1 is a perspective view of a magazine showing the advertising novelty of this invention incorporated therein;

Fig. 2, likewise in perspective, illustrates one manner of inserting the novelty in a magazine or book;

Fig. 3 represents a page having a plurality of 50 flaps;

Fig. 4 illustrates the perforated edge flap; Fig. 5 shows the invention applied to a single piece, shown opened out; and

Fig. 6, in perspective, shows the invention applied to a book or magazine, the sheets being 5 sealed on three sides to form a pocket for containing a card, premium or the like.

In Fig. 1 is represented a book, magazine, booklet or the like 1, in a certain part of which—more particularly, between group of pages 2 and 10 group 3—is incorporated the novelty of this invention. The free edges 6 of two succeeding sheets, namely, 4 and 5, are closed (as will be more fully described presently) so as to conceal the printed matter on the inner pages of the said 15 pair of sheets. For convenience the first page (exposed) of the pair of sheets 4 and 5 is given a page number "35". In the exposed page (folio "35") of sheet 4 is formed a flap 10 as by slitting three sides, namely, 11, 12 and 13, there- 20 of, leaving the fourth side 14 intact and uncut. There may be provided, as on side 12, a small finger nail recess 15, to facilitate the opening of flap 10. The finger nail recess may be cut into the flap (as 15 in Fig. 1) or it may be 25 cut into the sheet bordering the flap (as 15' in Fig. 2).

The flap 10, which need not have a rectangular shape as shown, nor be oriented in the particular position shown, may form part of a picturization printed on exposed page "35" and be harmonized therewith; the flap may define an object depicted in the said picturization, the sides, 30 11, 12, 13, 14 forming the outline of the object or other matter which preferably would be an essential element of the picturization or advertisement. Instead of a single flap (as in Fig. 1) there may be provided a plurality of flaps, as 35 will be described in connection with Fig. 3.

The exposed page of sheet 4 (folio "35") is 40 thus effective to conceal or cover the printed matter appearing on the facing page of sheet 5 (folio "37"), more particularly, flap 10 conceals or covers certain printed matter appearing on said folio "37", which can only be discerned or 45 read by opening the flap by folding it back on its uncut edge 14 (as shown in dot-and-dash lines in Fig. 1). By thus swinging back flap 10, not only is the message appearing on inner folio "37" brought to light, but also the printed matter on 50 the reverse side of the flap itself becomes readable.

The flap (or flaps) may be formed in the first page (folio "35") of the first of the two pair of succeeding sheets 4 and 5, as has been shown in 55

Fig. 1, or the flap (or flaps) may be formed in the second sheet 5 (which would be folio "38") as shown in dotted lines in Fig. 1 and designated 10', or flaps may be provided in both sheets.

The free edges 6 of the pair of succeeding sheets may be closed adhesively or the sheets may be formed by folding a larger blank and leaving the fold therein. Where the novelty is 10 to be incorporated into a magazine, book or pamphlet or the like, the manner of insertion shown in Fig. 2 might be preferred. Sheets 4 and 5 together with sheet 7 (which forms folios "33" and "34", as will be seen) are formed from 15 a large (triple sheet) blank, folded to form fold 6' and fold 8. This is inserted where required in magazine or book 1, Fig. 2, with fold 6' at the outward edge and with fold 8 at the inner edge, where it is bound together with the other 20 sheets of the magazine or book. It is understood that the inserted sheets 4—5—7 will have the flap or flaps already formed therein. If the magazine or book is to be trimmed subsequently to the insertion of the novelty sheets, fold 6' 25 will be made short so as to escape the trimming knives. The sheet 7 may be omitted and the two sheets 4 and 5 bound in the volume at edges 8, or a short extension strip (not shown) may be provided for the binding operation.

30 Instead of a single flap as 10, Fig. 1, there may be provided a plurality of flaps such as 16, 17, Fig. 3, the flaps forming part of the picturization. In Fig. 3 this is the representation of a dwelling, and flaps 16 represent windows and flap 17, the door. Flap 17 is similar to flap 10, being slit on three sides and foldable on the fourth, uncut side (the hinged edge of the door). The window flaps may be similar; in Fig. 3, these (16) are shown as double, i. e., comprising 40 two halves 16a and 16b foldable, respectively, on uncut sides 14a and 14b.

Instead of being slit, the three edges 11', 12' and 13', see Fig. 4, of the flap may be perforated, scored or otherwise treated, so that these edges 45 must be broken before the flap can be opened. There may be provided an opening 18 for the insertion of the finger tip or an instrument to inaugurate tearing along the perforated edges.

In addition to the slit along three sides of the 50 flap, as in Fig. 2, the fourth side, designated 14' in this figure, may be perforated or scored, so that not only the flap be opened on side 14' but the entire flap 10' (which might constitute a coupon, mailing card and the like) might be 55 removed by severing along perforated edge 14'.

The invention, in any of the forms above described, may be applied as a single piece, i. e., divorced from a book, magazine or the like; this is shown in Fig. 5, wherein the sheets are designated, as before, 4 and 5, and the flap, 10. The single piece novelty is formed from a blank, as shown in Fig. 5, which is folded on line 20 to bring free edge 6'' on line 26 and adhesive edging 21 folded thereover to seal that edge; top adhesive edging 22 and bottom adhesive edging 23 are then folded over to seal the top and bottom of the piece. The piece is thus sealed on all sides; and the sole or dominant message intended to be conveyed is discerned by opening flap 10, the three edges of which may be slit or perforated, as already described. The two sheets may have their three edges attached together by means of adhesive applied to the sheet 75 along and close to these edges without the pro-

vision of the edging strips or extensions 21, 22 and 23.

A similar closing of all three edges may be applied where the novelty is incorporated in a book or magazine, as shown in Fig. 6. Edgings 5 21', 22' and 23', coated with adhesive, formed as extensions of sheet 5, are folded over the corresponding edges of sheet 4 and sealed thereover. Flap 10 in sheet 4 (or in sheet 5) provides the means for reading the concealed message. Instead of providing edges to close the edges as shown, these edges may be sealed together by means of adhesive applied to the sheet close to and along the edges. The outer edge may be folded as in Fig. 2, requiring only the top and 15 bottom edges to be closed adhesively, with or without the use of edging strips.

Where all three edges are closed, whether in the single piece novelty of Fig. 5 or whether incorporated in a magazine or book as in Fig. 6, 20 a pocket or compartment is formed in which may be placed a coupon, card, premium or the like 3, which can be abstracted therefrom only through the flap 10. Where the three edges of the flap are not slit but perforated or scored, as shown in Fig. 6, assurances are provided that the card, ticket, coupon or premium will be abstracted by no one except the recipient of the magazine or book, to whom it comes with the seal—flap perforations—unbroken.

Although for ease in illustration and description, the flaps have been shown as rectangular, it is clear that they may be made of any desired shape or outline, having either straight or curved sides, and may be either symmetrical or irregular.

I claim:

1. In a novelty of the class described, a plurality of sheets constituting a book, a pair of successive sheets of which are closed together along the edges thereof, a flap formed in the exposed page of the first of the said pair of sheets adapted to be folded back to expose the reverse side of the flap and the inner page of the second of the said pair of sheets, and a flap formed in the said second sheet adapted to be folded back to expose the reverse side of the flap and the inner page of the said first sheet.

2. In a novelty of the class described, a plurality of sheets constituting a book, a pair of successive sheets of which are closed at the top, 50 outer and bottom edges to form a pocket adapted to contain therein a card or the like, and a flap formed in one of the sheets adapted to be folded back to gain access to the said pocket and the said card contained therein.

3. In a novelty of the class described, a plurality of sheets constituting a book, a pair of successive sheets of which are closed together along their edges to form a pocket adapted to contain therein a card or the like, and a flap 60 formed in one of the said sheets by perforating along a portion of its perimeter, the said flap being adapted after severing along the said perforation, to be folded back on the unperforated perimetric portion to gain access to the said card contained in the said pocket.

4. In a novelty of the class described, a plurality of sheets constituting a book, a pair of successive sheets of which are closed together along the edges thereof, a flap formed in one of the said sheets by perforating along a portion of its perimeter, there being an opening for the insertion of the finger tip or an instrument to inaugurate the severance of the said perfora- 75

tion, the said flap being adapted after severance, to be folded back on the unperforated perimetric portion.

5. In a novelty of the class described, a plurality of sheets constituting a book, a pair of successive sheets of which are closed together along the edges thereof, and a flap formed in one of the said sheets by perforating along a portion of its perimeter, the said flap being adapted 10
10 after severing along the said perforation, to be folded back on the unperforated perimetric portion.

6. In a novelty of the class described, a plurality of sheets constituting a book, a pair of successive sheets of which are closed along edges thereof, the exposed page of one of the sheets bearing thereon a picturization, and at least one flap, the outlines of which define objects or parts 15
15 of the said picturization, formed in the said sheet by slits along a perimetric portion thereof, and adapted to be folded back to expose the inner page of the said succeeding sheet.

7. In a novelty of the class described, a plurality of sheets constituting a book, a pair of succeeding sheets of which are closed together along the outer, bottom and top edges thereof, the exposed page of one of the said sheets being provided with a flap severable along a portion 20
20 of its perimeter and foldable on the unsevered

portion thereof, to expose the inner page of the said succeeding sheet.

8. In a novelty of the class described, a plurality of sheets constituting a book, a pair of successive sheets of which are closed together along the free edge thereof, and at least one flap formed in one of the said sheets, slit along a portion of its perimeter and adapted to be folded back on the uncut perimetric portion. 5

9. In a novelty of the class described, a plurality of sheets constituting a book, a pair of succeeding sheets of which are closed together along edges thereof, the exposed page of one of the sheets bearing thereon a picturization, and at least one flap formed in the said sheet, the outlines of which define an object or part of the said picturization, the inner page of the said succeeding sheet bearing thereon a further picturization, the said flap being adapted to be folded back to expose the said inner page, the picturization of which harmonizes at the said opening with the picturization of the exposed page 10
15
15 of the first mentioned sheet.

10. In a novelty of the class described, a plurality of sheets constituting a book, a pair of successive sheets of which are connected together by an uncut fold, and a flap formed in one of the said sheets adapted to be folded back to expose the matter printed on the inner page. 20
